(57) **CLAIM**

The ornamental design for a fragrance membrane housing component, as shown and described.

DESCRIPTION

FIG. 1 is a right front top perspective view of a fragrance membrane housing component showing my design;
FIG. 2 is left rear bottom perspective view of the fragrance membrane housing component of FIG. 1;
FIG. 3 is a front elevational view of the fragrance membrane housing component of FIG. 1;
FIG. 4 is a rear elevational view of the fragrance membrane housing component of FIG. 1;
FIG. 5 is a top view of the fragrance membrane housing component of FIG. 1;
FIG. 6 is a bottom view of the fragrance membrane housing component of FIG. 1;
FIG. 7 is a right side elevational view of the fragrance membrane housing component of FIG. 1; and,
FIG. 8 is a left side elevational view of the fragrance membrane housing component of FIG. 1.
The broken lines in the Figures show environmental subject matter and portions of the article that form no part of the claimed design.
